Term of patent 14 years

(Cl. D57—1)

Fig. 1.

Fig. 2.

Fig. 3.

Fig. 4.

FIG. 1 is a front elevational view of a spectacle frame embodying our new design;

FIG. 2 is a side elevational view thereof;

FIG. 3 is a detailed sectional view taken on the line 3—3 of FIG. 1; and

FIG. 4 is a detailed sectional view taken on the line 4—4 of FIG. 2.

The side not shown is substantially the same as the side shown.

The characteristic features of our design for the spectacle frame disclosed reside in the surface ornamentation applied to the front, at the ends of the frame, and on the temple portions thereof as shown.

We claim:

The ornamental design for a spectacle frame, substantially as shown and described.
